UNITED STATES PATENT OFFICE.

LOUIS ISAAC AND RAPHAEL GROSS, OF NEW YORK, N. Y.

ORNAMENTED CANVAS SHOE.

1,294,667.

Specification of Letters Patent. Patented Feb. 18, 1919.

Application filed June 7, 1918. Serial No. 238,627.

To all whom it may concern:

Be it known that we, LOUIS ISAAC and RAPHAEL Gross, citizens of the United States, and residents of borough of Manhattan, city, county, and State of New York, have invented certain new and useful Improvements in Ornamented Canvas Shoes, of which the following is a specification.

This invention relates to means of ornamentation for canvas shoes, and our improvement is directed particularly to the production of embroidery tabs, constituting designs of suitable character, worked upon canvas mounts, and applied as by stitching, 15 directly upon the shoe vamp, to form an integral part thereof.

The purpose of our invention is to enable canvas shoes to be ornamented with a fac- 20 ing of embroidery in an economical and ef- fective manner, without the necessity of working the embroidery design into the material of the vamp, while at the same time securing all the effect of so doing. It con- 25 sists therefore in producing an embroidered design, as by machine work, upon a mount of canvas, and then in stitching the em- broidered article upon the canvas vamp.

It is of importance that the embroidered mount or article should be of canvas, in or- 30 der that its texture may correspond with that of the vamp; because, in this way, when said mount is stitched upon the vamp, it will thus form an integral part thereof, and assume with the vamp the shape or con- 35 tour which the latter is given, over the area of application, in the stretching of the vamp over a last for production of the shoe upper. Furthermore, it will permit the vamp, or upper forward portion thereof, near the 40 instep, to yield freely with the working of the wearer's foot.

Metal or other stiff buckles and the like, in their application to shoes, are usually se- 45 cured to a tongue which projects upwardly from the vamp, to extend over the instep. If such stiff articles of ornamentation were secured upon the upper, forward portion of the shoe, the effect would be to interfere with the flexible adaptability of said shoe 50 portion which would thus be less free to yield in consonance with the movement of the wearer's foot, that is snugly incased by the canvas shoe.

The machine-produced embroidery device 55 which is thus made a homogeneous part of

the vamp, presents all the desired effects of embroidered ornamentation worked into the material of the vamp, but at a fraction of the expense of such operation.

Besides, embroidery stitches through the 60 vamp would at the reverse side create pro- tuberances, which, with a snugly fitting shoe, by projecting from the inner, otherwise smooth surface of the canvas, would bear uncomfortably and injuriously upon the 65 flesh.

But with our applied tabs or pieces of canvas, bearing the embroidery, which are simply sewn to the canvas of the vamp, the stated ill effect is entirely avoided, while the 70 embroidery effect is fully achieved.

In the drawing,

Figure 1 is a view of a piece of canvas comprising a vamp, having imposed thereon the embroidery mount.

75

Fig. 2 is a plan view of a formed shoe and

Fig. 3 is a section on the line 3—3 of Fig. 1.

In carrying out our invention we take a 80 piece or strip of canvas, as *a*, which is of suitable size and shape to lie upon the front upper portion of a shoe vamp, and we em- 85 broider a design, as *b* thereon, also binding the surrounding edge of said piece as at *c*. Said piece or strip *a*, which we term an em- 90 broidery mount, is then secured upon a can- vas vamp as *d*, see Fig. 1, before the latter is shaped to the contour of a shoe upper, as shown in Fig. 2.

In securing the mount *a* to the vamp we sew it thereon with stitches *e*, drawn over the binding *c*, so that said stitches become embedded therein, and, being of the same color as the canvas, are thus invisible.

95

The vamp and mount, being of the same canvas material, besides corresponding in color, constitute a fabric characterized by homogeneity of texture, to thus accommodate itself uniformly to the variations of 100 contour such as will occur in service—through the flexing of the wearer's foot, and through the influences of moisture and dry- ness to which it will be subjected.

We claim:—

In a shoe, the combination with a canvas vamp of a canvas mount bearing embroidery, said mount having its surrounding edge bound with embroidery, and said mount being secured to said vamp by stitches em- 110

105

bedded in said edge binding, whereby said mount comprehends a like appearing, flexing and wearing part of said vamp, indistinguishable therefrom as to the character-
istic whereby the embroidery borne by said mount appears to have been worked directly on said vamp.

Signed at borough of Manhattan in the

city, county and State of New York this 3rd day of June A. D. 1918.

LOUIS ISAAC.
RAPHAEL GROSS.
